UNITED STATES PATENT OFFICE

167,769

COMBINED STARTING PULLEY AND BLOWER FOR A GASOLINE ENGINE

William H. Phelps, Ralston, Nebr.

Application October 20, 1951, Serial No. 17,043

Term of patent 14 years

(Cl. D77—1)

To all whom it may concern:

Be it known that I, William H. Phelps, a citizen of the United States, residing at Ralston, county of Douglas, and State of Nebraska, have invented a new, original, and ornamental Design for a Combined Starting Pulley and Blower for a Gasoline Engine, of which the following is a specification, reference being had to the accompanying drawing, forming a part thereof, in which:

Fig. 1 is a top plan view; Fig. 2 is a side elevational view; and Fig. 3 is a bottom plan view of a combined starting pulley and blower for a gasoline engine showing my new design.

I claim:

The ornamental design for a combined starting pulley and blower for a gasoline engine, as shown.

WILLIAM H. PHELPS.
